Primary Examiner—Raphael Barkai**[57] CLAIM**

The ornamental design for a foldable hanger, as shown and described.

DESCRIPTION

FIG. 1 is a top plan view of a foldable hanger embodying my design in the open position;

FIG. 2 is a front elevational view of the foldable hanger as shown in FIG. 1, the rear view being a mirror image thereof; FIG. 3 is a right side elevational view of the foldable hanger as shown in FIG. 1;

FIG. 4 is a left side elevational view of the foldable hanger as shown in FIG. 1;

FIG. 5 is a top plan view of the foldable hanger as seen in FIG. 1, but in a closed configuration;

FIG. 6 is a front elevational view of the foldable hanger as shown in FIG. 5, the rear view being a mirror image thereof; and,

FIG. 7 is a bottom plan view of the foldable hanger as shown in FIG. 1.
